INVENTOR

BY Victor J. Evans

ATTORNEY

Victor J. Evans

WITNESS:

UNITED STATES PATENT OFFICE.

THEODORE J. DECK, OF BALTIMORE, MARYLAND.

TOY ARROW.

Application filed June 9, 1922. Serial No. 567,133.

To all whom it may concern:

Be it known that I, THEODORE J. DECK, a citizen of the United States, residing at Baltimore, in the county of Baltimore and 5 State of Maryland, have invented new and useful Improvements in Toy Arrows, of which the following is a specification.

This invention relates to a toy or amusement device, the general object of the invention being to provide an arrow projecting device which comprises a holder for the arrow and a resilient member for projecting the arrow therefrom.

Another object of the invention is to provide a cap for the arrow which is provided with a point which will engage the target and hold the cap thereto, thus permitting the arrow to be used several times with new caps so that all the shots hitting the target 20 can be seen by the caps sticking thereto.

This invention also consists in certain other features of construction and in the combination and arrangement of the several parts, to be hereinafter fully described, illustrated in the accompanying drawings and 25 specifically pointed out in the appended claim.

In describing my invention in detail, reference will be had to the accompanying drawings wherein like characters denote like or corresponding parts throughout the several views, and in which:—

Figure 1 is a side view of the invention.

Figure 2 is an end view thereof.

Figure 3 is an elevation of a modification, parts being shown in section.

Figure 4 is an end view of a modified form of arrow.

Figure 5 is a side view of Figure 4.

Figure 6 is a sectional view of this form.

Figures 7, 8 and 9 are views of another form of arrow cap.

In these views, 1 indicates a spool-like member which is provided with a bore to receive an arrow 2. A band 3 of rubber or the like is secured to said member by the staples 4 in such a manner that a loop part may engage the projecting end of the arrow so that the arrow and said loop part may be drawn rearwardly by the thumb and forefinger of one hand, while the other hand is holding

the member 1. This will stretch the band so that when it is released it will spring back to its original shape and thus cause the arrow to be projected from the bore of the member and thrown a distance therefrom. The member may be provided with a handle 5, if desired.

Figure 3 shows a slightly different form of the device. In this form the endless band 3' has its ends engaging the staples 4' instead of being looped over the member as shown in Figures 1 and 2. In the first form only one part of the band engages the arrow while in the second form both parts of the band engage the arrow.

I provide a plurality of caps for the end of the arrow, each cap having a pointed member 6 at its closed end, the head of which rests against the end of the arrow. 70 The cap is shown at 7. Thus when the arrow strikes the target or other object at which it is shot the pointed member will enter the same and thus hold the cap to the target so that the arrow can be withdrawn from the 75 cap and the same left sticking to the target. A new cap can then be put on the arrow and the same shot again. Thus each shot will be registered on the target so that the closest can be seen after the round has been shot. 80

Figures 4, 5 and 6 show a cap provided with four wings 8 while Figures 7, 8 and 9 show a cap provided with two wings 9. These wings facilitate the flight of the arrow and adds to the attractiveness of the device. 85

Attention is called to the fact that an ordinary tack may be used as the pointed member and as the same is removably held in the cap it can easily be replaced if lost or 90 when the point is dulled. The sharp point of the tack ensures the arrow sticking to the target or other object. It will, of course, be understood that the caps can be fastened to the arrow or that a plurality of arrows, each 95 provided with a cap, may be used, so that it is not necessary to remove the cap from the arrow or leave the cap sticking in the target and remove the arrow therefrom.

It is thought from the foregoing description that the advantages and novel features of my invention will be readily apparent.

I desire it to be understood that I may make changes in the construction and in the combination and arrangement of the several parts, provided that such changes fall within the scope of the appended claim.

Having thus described my invention what I claim as new is:—

An arrow having a tapered end, a tack

having its head engaging the flat extremity of the tapered end, a removable paper cap fitting over the tapered end and having a hole therein through which the pointed end of the tack passes and wings upon the cap.

In testimony whereof I affix my signature.

THEODORE J. DECK.
